Primary Examiner — Ramzi Almatrahi(74) *Attorney, Agent, or Firm* — Finnegan, Henderson, Farabow, Garrett & Dunner, LLP**CLAIM**

The ornamental design for a video capture device, as shown and described.

DESCRIPTION

FIG. 1 is a top, front and left side perspective view of a video capture device showing our new design;

FIG. 2 is a bottom, front and right side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines of even length shown in the drawings illustrate portions of the video capture device that form no part of the claimed design.
